UNITED STATES PATENT OFFICE.

JOSEPH L. HILLER, OF MATTAPOISETT, MASSACHUSETTS, ASSIGNOR TO PENNSYLVANIA CRUSHER COMPANY, OF NEW YORK, N. Y.; A CORPORATION OF NEW YORK.

COAL-BREAKER CONSTRUCTION.

1,254,137.

Specification of Letters Patent. Patented Jan. 22, 1918.

Original application filed May 1, 1911, Serial No. 624,291. Divided and this application filed April 9, 1915. Serial No. 20,275.

To all whom it may concern:

Be it known that I, JOSEPH L. HILLER, a citizen of the United States, and a resident of Mattapoisett, Plymouth county, Massachusetts, have invented certain Improvements in Coal-Breaker Constructions, (being a division of my application for patent filed May 1, 1911, Serial No. 624,291,) of which the following is a specification.

- 10 10 One object of this invention is to provide a rotary coal breaker with a novel form and arrangement of lifting and screening shelf particularly designed to reduce the power required for operating and also to lessen the time necessary for a given body of material, such as coal in lump form, to be brought to a definite fineness;—it being also desired that the construction shall be such as to permit of the shelf being adjusted to vary 15 the distance of one of its edges from the adjacent surface of the drum in order to suit it for the passage of pieces of different sizes.

These objects and other advantageous ends I secure as hereinafter set forth, reference being had to the accompanying drawings, in which,

Figure 1 is a fragmentary transverse section of a portion of a rotary coal breaker drum showing my invention as applied thereto;

Fig. 2 is a fragmentary longitudinal section of a part of the drum shown in Fig. 1, illustrating imperforate plows in place of the perforated structures shown in Fig. 1, and,

Fig. 3 is a section on an enlarged scale further illustrating the construction of one of the features of the invention.

- 40 40 In the above drawings I have illustrated a rotary drum 1 formed of perforated sheet or plate metal supported on a frame formed by end structures including radiating arms 2 and 3 rigidly connected at their outer extremities by longitudinally extending members 4 which serve to directly support said perforated cylinder or drum. The breaker is driven by power applied through an annular gear 5 fixed to one end of the frame and at intervals within the drum I provide lifting shelves, of which one is illustrated at 50 6, in the form of flat perforated plates rigidly supported by a suitable number of

angle brackets 7 so that they extend inwardly from the drum surface in substantially radial planes. Said brackets are usually made so that their plate engaging faces are substantially at right angles to the faces designed to engage the drum structure 1, and as shown in Fig. 3, the bolts 8 employed to hold these brackets in place may be utilized to also clamp the perforated plate forming the drum 1, to the frame members 4. Each of the plates constituting the shelves 6 is held to its brackets by bolts 9 which extend through radially elongated slots therein so as to permit of the adjustment of the plate toward or from the drum surface;—it being my intention to operate the machine with the adjacent edge of the shelf spaced away from said surface as shown in Figs. 1 and 3.

In addition to the radial shelves 6 I may also employ any desired number of perforated shelves or plows 10 mounted on supporting brackets 11 so fixed to the supporting frame or drum structure that said shelves extend in a plane at an angle to the plane of the adjacent radial plate or plates 6. In this case also there is a space between the drum surface 1 and the adjacent edge of said plate, which in addition to serving to raise material, gives it a movement longitudinally of the drum. In the case shown in Fig. 2 I employ a number of inwardly projecting plates or plows 12 in place of the inclined plates 10, and instead of slotting the brackets 7 to permit of adjustment of the plates 6, in this case I provide slots in said plate for the bolts 9 so that as before it is possible to vary the distance between the drum and the adjacent edge of said shelf or plate.

Under operating conditions the drum is supplied with a definite quantity of coal or other material to be broken and is rotated at a suitable speed so that this material, which is in lump form, is carried up by each of the shelves 6. As one of the shelves, for example, rises owing to the rotation of the drum, the fine material carried up by it passes to a greater or less extent through its perforations as well as through the space between it and the adjacent edge of the shelf, thereafter passing out of the drum through the perforations thereof. Ulti-

mately the material carried up by the shelf 6 is discharged therefrom when it reaches the upper part of the drum and in falling to the bottom of the breaker is broken into small pieces, it being obvious that the material which escapes between the edges of the shelves and the drum is quickly discharged through the perforations thereof.

With the construction shown the amount 10 of power required to drive the drum is materially reduced by the use of my invention, since as pointed out the fine material is rapidly carried up and permitted to escape through the perforations of the shelves 15 as well as through the elongated openings between said shelves and the drum surface.

By inclining the shelf as shown in Fig. 1 a movement longitudinally of the drum is imparted to the material acted upon as it is 20 raised, which materially facilitates the quick separation of the fine from the coarse material especially when used in connection with shelves of the type shown at 6; and likewise cuts down the power necessary to break and 25 screen a given mass of material. Moreover any hard unbreakable pieces are ultimately moved to one end of the drum where they are discharged by a suitable device.

I claim:—

1. The combination of a rotatable screen 30 drum; brackets mounted therein and each having a slot extended radially of the drum; a shelf carried by the brackets; with clamping members passing through the slots of said brackets and adjustably clamping said shelf thereto at a distance from the inner surface of the drum.

2. The combination of a perforated screen 40 drum; a number of series of radially slotted brackets extending inwardly from the inner surface thereof; with flat perforated plates rigidly held to the brackets of said series and adjustable with their outer edges spaced away from the adjacent surface of the drum.

3. The combination of a screen drum; a 45 series of shelves projecting radially inward therein and extending longitudinally of the drum; with a second series of shelves also projecting inwardly in the drum but inclined to the lines of the shelves of the other series, the shelves of both series being rigidly fixed in positions with their edges spaced away from the drum surface to which they are adjacent.

JOSEPH L. HILLER.
